(57) **CLAIM**

The ornamental design for a vanity mirror, as shown and described.

DESCRIPTION

FIG. 1 is a top plan view of a vanity mirror showing our new design;

FIG. 2 is a bottom plan view thereof;

FIG. 3 is a front perspective view thereof;

FIG. 4 is a rear perspective view thereof;

FIG. 5 is a front view thereof;

FIG. 6 is a rear view thereof;

FIG. 7 is a cross-sectional view taken along line 7-7 in FIG. 5 thereof;

FIG. 8 is a cross-sectional view taken along line 8-8 in FIG. 5 thereof;

FIG. 9 is a left side view thereof, the right side view being a mirror image;

FIG. 10 is a left side view thereof, the right side view being a mirror image; and,

FIG. 11 is a left side view thereof, the right side view being a mirror image.

Alternative positions of the mirror are shown in FIGS. 10 and 11 to illustrate that the mirror can be rotated relative to the base around line 7-7 in FIG. 5.

The curved oblique lines are surface shading used to indicate the concave character of the rear mirror surface of the claimed design.
